UNITED STATES PATENT OFFICE.

LANDIS H. WIRT, OF SOUTH BEND, INDIANA.

TABLE ATTACHMENT FOR BATHTUBS.

Application filed April 12, 1924. Serial No. 706,043.

To all whom it may concern:

Be it known that I, LANDIS H. WIRT, a citizen of the United States, residing at South Bend, in the county of St. Joseph 5 and State of Indiana, have invented certain new and useful Improvements in Table Attachments for Bathtubs, of which the following is a specification.

The invention relates to attachments for 10 bath tubs, and has for its object to provide a horizontally disposed table supported by the outer side of the bath tub, and by the wall adjacent the inner side of the bath tub, and on which table infants may be 15 placed, bathed and dressed in a position where water within the tub may be easily reached for the bathing operation.

A further object is to provide the table at 20 one side thereof with adjusting means whereby when the supporting legs are in engagement with the outer side of the tub, the device may be accommodated to different widths of tubs, which necessarily will vary the distance of the wall adjacent the tub 25 from the outer side of the tub.

A further object is to provide the under 30 side of the table with hinged supporting legs substantially V-shaped and provided with inset portions for receiving the outer side of the tub, said supporting legs being foldable onto each other under the table, thereby allowing the device to be folded into a compact package for storage or shipping purposes. Also to provide the vertical portions 35 of the supporting legs with pivotally connected braces, the upper ends of which are provided with angularly disposed arms adapted to be received in apertures of the frame of the table for bracing and holding 40 said legs rigidly when in engagement with the side of a tub, said braces, when the device is collapsed, fold into position substantially in the same plane as the legs, thereby allowing the device to be folded into a compact 45 package.

A further object is to provide the inner side of the table top with outwardly adjustable rods for engaging a wall, which rods extend through eyes of eye bolts, and are 50 clamped in adjusted positions by means of thumb nuts carried by said eye bolts.

With the above and other objects in view 55 the invention resides in the combination and arrangement of parts as hereinafter set forth, shown in the drawing, described and claimed, it being understood that changes

in the precise embodiment of the invention may be made within the scope of what is claimed without departing from the spirit of the invention.

In the drawings:—

Figure 1 is a perspective view of the table, showing the same applied to a conventional form of bath tub.

Figure 2 is a vertical transverse sectional view through a tub and portion of a wall, showing the table applied thereto.

Figure 3 is a bottom plan view of the table.

Figure 4 is a detail sectional view taken 70 on line 4—4 of Figure 3.

Figure 5 is a detail perspective view of a portion of the table frame and a portion of one of the leg braces.

Referring to the drawing, the numeral 1 75 designates a conventional form of bath tub, 2 the outer side thereof and 3 the inner side. The bath tub is disposed adjacent a wall 4 in the usual manner. It has been found in bathing infants that the operation is extremely difficult, and often a dangerous one, especially in bath tub. To facilitate the bathing and dressing operation a table 5 is provided, which table is disposed above the bath tub at a convenient height, whereby it will not be necessary to lean over a great distance while bathing and dressing the infant. The table 5 comprises a rectangular shaped frame 6 which surrounds a board 7. The board 7 may be formed from any kind 80 of material, however is preferably formed from stiff fibre board, and on which board the infant is placed during a washing and dressing operation, and consequently is supported over the tub where water may be 85 easily reached for sponging and bathing the infant. Hingedly connected at 8 to the inner opposite sides of the frame 6 are V-shaped supporting legs 9, which legs have their vertical portions 10 outwardly disposed and provided with inset portions 11, thereby forming horizontally disposed arms 12 for engaging the upper side of the outer side 2 of the tub, and supporting the outer side of the table 5. To prevent outward or 90 inward movement of the V-shaped legs 9 after they have been moved to vertical positions for supporting the table top, the pivoted braces 13 are moved to positions where they will incline upwardly inwardly towards each other, thereby allowing their angularly shaped ends 14 to be received in apertures 15

- in the frame 6 as clearly shown in Figures 1 and 5, therefore it will be seen that the legs will be rigidly braced. The braces 13 are provided with coiled portions 16, which surround the vertical portions 10 of the V-shaped legs, and are held against axial movement by means of pins 17 which extend through the portions 10 of the legs at the upper and lower sides of the coiled portions
- 10 16. When the legs are folded onto each other in engagement with the under side of the table top 5 as shown in Figure 3, the braces 13 are also folded to position in engagement with the under side of the table top, and substantially in the same plane as the V-shaped legs, therefore it will be seen that the device may be folded into a compact package for shipping and storage purposes, and will require very little room.
- 15 20. The V-shaped legs and the braces 13 are preferably formed from relatively heavy wire, thereby allowing the device to be cheaply manufactured and sold.

25 The inner side of the table top 5 is disposed adjacent the wall 4, however it is obvious that bath tubs vary in width, and to accommodate the device to bath tubs of various widths, adjustable wall engaging rods 18 are provided, which rods may be adjusted inwardly and outwardly according to the distance of the wall 4 from the outer side 2 of the bath tub, therefore it will be seen that the device may be adjusted for supporting the table 5 in a horizontal plane 30 when applied to bath tubs of different widths. The wall engaging rods 18 extend through eyes 19 of eye bolts 20, which eye bolts extend through opposite sides of the table top frame 6 and are provided with 35 thumb nuts 21, which thumb nuts when tightened securely clamp the rods 18 against the blocks 22 in the corners of the frame, which blocks are preferably recessed at 23 to allow a more perfect clamping operation and freedom of movement of the eyes 19 40 during the clamping operation. It will be noted that the table is supporting entirely 45 by the wall 4 and the outside 2 of the tub,

and by supporting the inner side of the table against the wall, special supporting legs for engaging the inner side of the tub are obviated, which is particularly advantageous where the inner side of the tub is imbedded in the wall, and consequently can not be used for supporting a table.

50 55 The invention having been set forth what is claimed as new and useful is:—

1. The combination with a wash tub disposed adjacent the wall, the outer wall of the wash tub, of a table, means for supporting said table, said means comprising hingedly mounted legs carried by the under side of the table and supporting one end of the table on the outer side of the wash tub, said legs being foldable against the under side of the table, and outwardly adjustable means carried by one side of the table and cooperating with the wall whereby the table is supported in a horizontal position.

60 70 75 2. A wash tub table comprising a platform, V-shaped legs hingedly connected to the under side of the platform and foldable onto each other and adapted to engage one side of a bath tub, pivoted braces carried by said legs at their outer ends, said braces being provided with angularly disposed arms adapted to be received in recesses of the platform, said legs being foldable onto the under side of the platform, outwardly adjustable rods carried by one end of the platform, said rods engaging the wall adjacent the bath tub, and in combination with the legs supporting the platform.

80 85 90 3. A bath tub table comprising a platform, hingedly connected V-shaped supporting legs carried by said platform and foldable onto the underside of the platform and adapted to receive one side of a bath tub, pivoted braces carried by said legs and cooperating with the platform and foldable onto the under side of the platform, and outwardly and inwardly adjustable wall engaging members carried by one end of the platform.

In testimony whereof I affix my signature.
LANDIS H. WIRT.
